(57) **CLAIM**

The ornamental design for a pair of in ear headphones, as shown and described.

DESCRIPTION

FIG. 1 is a perspective view of a pair of in ear headphones showing our new design;

FIG. 1A is a perspective view of a pair of in ear headphones as shown in FIG. 1, with the addition of an enlarged section depicting the intricacies of the new design.

FIG. 2 is a front view thereof;

FIG. 3 is a rear view thereof;

FIG. 4 is a side elevation view of a pair of in ear headphones with one in ear headphone shown separately for ease of illustration;

FIG. 5 is an opposite side elevational view of a pair of in ear headphones with one in ear headphone shown separately for ease of illustration;

FIG. 6 is a top view thereof;

FIG. 7 is a bottom view thereof.

FIG. 8 is a perspective view a second embodiment of a pair of in ear headphones showing our new design.

FIG. 9 is a front view thereof;

FIG. 10 is a rear view thereof;

FIG. 11 is a side elevational view of a pair of in ear headphones with one in ear headphone shown separately for ease of illustration;

FIG. 12 is an opposite side elevational view of a pair of in ear headphones with one in ear headphone shown separately for ease of illustration;

FIG. 13 is a top view thereof;

FIG. 14 is a bottom view thereof;

FIG. 15 is a perspective view of a third embodiment of a pair of in ear headphones showing our new design.

FIG. 16 is a front view thereof;

FIG. 17 is a rear view thereof;

FIG. 18 is a side elevational view of a pair of in ear headphones with one in ear headphone shown separately for ease of illustration;

FIG. 19 is an opposite side elevational view of a pair of in ear headphones with one in ear headphone shown separately for ease of illustration;

FIG. 20 is a top view thereof; and,

FIG. 21 is a bottom view thereof.

The broken lines showing the environment in the Figures are for illustrative purposes only and form no part of the claimed design.
